UNITED STATES PATENT OFFICE.

MAX STRAUS, OF BALTIMORE, MARYLAND.

FURNITURE-LEG SHOE.

SPECIFICATION forming part of Letters Patent No. 319,342, dated June 2, 1885.

Application filed March 28, 1884. (No model.)

To all whom it may concern:

Be it known that I, MAX STRAUS, a citizen of the United States, residing at Baltimore city, and State of Maryland, have invented 5 certain new and useful Improvements in Furniture-Leg Shoes, of which the following is a description.

Figure 1 is a plan view of a square form of furniture-leg shoe. Fig. 2 is a plan view of a 10 circular form of the same. Fig. 3 is a plan view of a rectangular form of the same. Fig. 4 is a sectional view on line xx of Fig. 1, and Fig. 5 is a sectional view on line yy of Fig. 2.

The object of my invention is to protect 15 from wear the carpets of rooms in which furniture having legs provided with casters is located; and to this end my invention consists of a shoe or plate having a central socket in its upper face provided with opposite notches 20 in its periphery to receive a caster-wheel, the top face of the shoe being also provided with an inclined plane or inclined planes leading from its periphery to the central socket for the easy passage of the caster-wheels to the 25 central socket, and ribs to guide the casters into the socket.

Referring to the drawings, a represents a 30 shoe or plate, which may be made of square, rectangular, circular, or any other desired form, and preferably has the outer edge of its lower face, which rests on the carpet of the room, chamfered to prevent wear of the carpet. b represents a socket formed in the upper face of the shoe. The periphery of the 35 socket b is provided with opposite notches or recesses c , having at their lower ends inclined planes d , each leading from the lower end of the recess c to the bottom of the socket b for the easy passage of a caster-wheel into the 40 socket b , the opposite sides of the circumference of a caster-wheel resting in the opposite recesses c , which retain the caster in place.

Leading from the periphery of the socket b to the periphery or outer edge of the shoe a 45 are arranged a series of inclined planes, d , for the easy passage of the caster-wheel up said inclined plane into the socket. h represents ribs extending from the periphery of the socket between each pair of recesses c to the 50 outer edge or periphery of the upper face of the shoe a . The ribs h serve to guide the caster-wheels up the inclined plane d and into

the socket b and opposite recesses c . The shoe or plate a may be made of square form, as shown in Fig. 1, the socket b in this case 55 being central and its periphery provided with recesses c , and four inclined planes, d , being employed, leading from the periphery of the socket b to the four sides of the shoe and provided with diagonal ribs h , for guiding the 60 caster-wheel as it ascends an inclined plane into the opposite recesses c in the socket b .

In Fig. 2 I have shown a shoe, a , of circular form provided with a central socket, b , a single circular inclined plane, d , being employed with guide-ribs h , each extending from the circumference of the shoe to the middle 65 of one of the spaces between the two recesses c .

In order to prevent the upper part of the 70 article of furniture having casters on its legs from coming in contact with the wall of a room, I employ a rectangular shoe, as shown in Fig. 3, with one of its ends abutting against the wash-board of the room and its socket arranged in the upper face of the shoe, and having inclined planes d and guide-ribs near its 75 opposite end, so that when the casters of the chair are in place in the socket the upper part of the chair will not be in contact with the wall of the room. The same result also could 80 be obtained by securing a projection of any form to the rear end of the shoe, so as to bear against the wash-board.

Having thus fully described my invention, what I claim as new, and desire to secure by 85 Letters Patent, is—

1. A furniture-leg shoe or plate, a , of any 90 desired form in its outer configuration, and provided on its upper face with a socket, b , and an inclined plane or planes, d , extending from the periphery of the socket to the periphery of the shoe, as set forth.

2. A furniture-leg shoe or plate, a , of any 95 desired form in its outer configuration, and provided on its upper face with a socket, b , having opposite notches c in its periphery, inclined plane or planes d , extending from the periphery of the socket to the periphery of the shoe, and guide-ribs h , as set forth.

MAX STRAUS.
